Primary Examiner — Patricia A Palasik

(74) *Attorney, Agent, or Firm* — Burns & Levinson LLP

CLAIM

The ornamental design for a mobile robot having an illuminated region, as shown and described.

DESCRIPTION

This design patent application contains seven drawings executed in color. Copies of this design patent application with color drawings will be provided by the Office upon request and payment of any necessary fees.

FIG. 1 is a perspective view of a mobile robot having an illuminated region from above the mobile robot.

FIG. 2 is a perspective view of the mobile robot from below the mobile robot.

FIG. 3 is a front view of the mobile robot.

FIG. 4 is a right side view of the mobile robot.

FIG. 5 is a left side view of the mobile robot.

FIG. 6 is a plan view of the mobile robot showing a top of the mobile robot; and,

FIG. 7 is a perspective view of a corner of the mobile robot.
